US00D996421S

(12) **United States Design Patent** (10) **Patent No.:** **US D996,421 S**
Tham et al. (45) **Date of Patent:** **** Aug. 22, 2023**

(54) **WEARABLE ELECTRONIC DEVICE**

(71) Applicants: **Yu Jiang Tham**, San Diego, CA (US); **Gerald Nilles**, Culver City, CA (US); **Jonathan M. Rodriguez, II**, Beverly Hills, CA (US); **Nir Daube**, Pacific Palisades, CA (US)

(72) Inventors: **Yu Jiang Tham**, San Diego, CA (US); **Gerald Nilles**, Culver City, CA (US); **Jonathan M. Rodriguez, II**, Beverly Hills, CA (US); **Nir Daube**, Pacific Palisades, CA (US)

(73) Assignee: **Snap Inc.**, Santa Monica, CA (US)

(**) Term: **15 Years**

(21) Appl. No.: **29/839,247**

(22) Filed: **May 19, 2022**

Related U.S. Application Data

(63) Continuation of application No. 29/804,711, filed on Aug. 23, 2021, now Pat. No. Des. 956,743, which is (Continued)
